UNITED STATES PATENT OFFICE

2,568,562

ANGLE COCK BRACKET

Charles R. Radey, Michigan City, Ind., assignor
to Pullman-Standard Car Manufacturing Com-
pany, Chicago, Ill., a corporation of Delaware

Application March 31, 1948, Serial No. 18,227

5 Claims. (Cl. 213—67)

1

The present invention relates to railway cars of the type that can be coupled together for making up a train of cars. More specifically, the invention has to do with the supporting bracket for the angle cock in the air line of a railway car in combination with a striking plate on the coupler housing. The air or train line comprises a pipe that extends the full length of the car and on one end of this pipe is an angle cock used for shutting off or turning on the flow of air through the pipe. A flexible hose is normally connected to the angle cock member for attaching a train line pipe of one car to that of the next car. The angle cock must be rigidly supported on the car and for this purpose the bracket forming the subject matter of the present invention is ideally suited. The bracket also serves as a backing member to reinforce the striking plate on the coupler housing and, therefore, provides a very rigid assembly. All of this is accomplished cheaply and the entire assembly lends itself ideally to mass production methods of fabrication.

The foregoing constitute some of the principal objects and advantages of the present invention, others of which will become apparent from the following description and the drawings, in which

Fig. 1 is a fragmentary end view of a railway car mounted on rails and showing the angle cock bracket assembly forming the subject matter of the present invention;

Fig. 2 is an enlarged, fragmentary plan view of the coupler housing illustrating the angle cock bracket disposed between the striking plate and the draft key slot liner in accordance with the present invention;

Fig. 3 is an end elevational view of that portion of the coupler housing assembly illustrated in Fig. 2; and

Fig. 4 is a side elevational view of the assembly illustrated in Fig. 3, the view being taken in the direction of line 4—4 of Fig. 1.

For purposes of illustration a specific embodiment of the present invention is shown in the drawings and will be described hereinafter. It is recognized, however, that modifications may be made in this specific embodiment without departing from the intended scope of the invention.

Referring to Fig. 1 of the drawings the invention is illustrated in connection with a railway car that is more or less diagrammatically illustrated at 10 that is mounted on wheeled trucks generally indicated at 11 equipped with flanged wheels 12 that roll along rails 13. At each end of the car 10 is a coupler assembly generally indicated at 14 that as shown is fitted into the car center sill 15.

2

The car center sill 15 is of the usual type that normally extends throughout the length of the car and comprises a pair of horizontally spaced vertical webs, one of which is shown at 16 in Fig. 5 connected together across their upper ends by a plate portion 17. An outwardly extending flange 18 is provided along the lower edge of each of the vertical webs 16. The coupler assembly 14 includes an upper striking plate member 19 (see Figs. 2 to 4 inclusive) that is somewhat massive in shape and is backed by suitable gussets indicated at 20 in Fig. 4. Extending downwardly from the upper striking plate 19 is a pair of horizontally spaced vertically disposed striking plates 21 (Fig. 1) that project outwardly beyond the webs 16 of the car center sill 15. Each of these vertical striking plates 21 is provided with a rearwardly extending web portion 22 that is attached to the inner side of the corresponding web 16 of the car center sill 15. Thus the striking plates 19 and 21 together with the center sill 15 form a coupler housing in which a coupler indicated at 23 in Fig. 1 can be mounted. The coupler 23 may be of any conventional type, the details of which form no part of the present invention.

In couplers of this type, however, there is provided a coupler yoke key (not shown) that projects through the side walls of the coupler housing and rides in a coupler key slot liner that is shown at 24 in Figs. 2 to 4. Such a key is provided on each side of the coupler yoke and consequently a key liner 24 is rigidly secured to each of the vertical webs 16 of the car center sill 15. As best shown in Figs. 2 and 4 the key liner 24 in each instance is spaced a certain distance behind the adjacent vertical striking plate 21. Between each striking plate 21 and the adjacent key liner 24 is an angle cock bracket 25 that is provided with a relatively wide portion that is adapted to engage the rear face of the vertical striking plate 21 and extends to and engages the adjacent key liner 24 and serves as a gusset for reinforcing the striking plate 21. The angle cock bracket 25 is also provided with an outwardly extending flange portion 26 that extends beyond the outermost edge of the adjacent vertical striking plate 21. This angle cock bracket is apertured at 27 and 28 to receive the arms of a U-shaped supporting clamp 29 (shown in Fig. 3). The conventional train line extends throughout the length of the car and is provided at each end with an angle cock indicated at 30 in Fig. 1 that likewise is conventional. This angle cock is illustrated diagrammatically in broken lines 31 in Fig. 3 and is securely fastened to the angle cock bracket 25 by means of the U-shaped clamp 29, the free ends

of whose arms are threaded to receive nuts 32. A flexible hose 33 is secured to the angle cock 30 and is used for coupling the train line of one car to the train line of a second car.

There is thus described an assembly that includes a coupler housing having vertical striking plates 21 that are rigidly gusseted by means of a bracket 25 that is welded or otherwise secured in place between the vertical striking plate 21 and the adjacent key liner 24. This bracket 25 thus serves to strengthen the coupler housing and striking plate assembly and is a rigid member in itself to function ideally as an angle cock bracket for supporting the train line angle cock.

Though a U-shaped clamp 29 is illustrated as means for attaching the angle cock to bracket 25 it is, of course recognized that other types of attaching clamps can be equally satisfactory.

I claim:

1. For use in a railway car, the combination of a coupler housing having a striking plate at its forward end that projects outwardly beyond the sides of the housing, a coupler yoke key liner disposed on the side of the housing and spaced from the striking plate, and an angle cock bracket disposed between and engaging the striking plate and the liner, the bracket projecting outwardly from the housing.

2. For use in a railway car, the combination of a coupler housing having a striking plate at its forward end that projects outwardly beyond the sides of the housing, a coupler yoke key liner disposed on the side of the housing and spaced from the striking plate, and an angle cock bracket disposed between and engaging the striking plate and the liner, the bracket providing a relatively flat plate projecting outwardly from the housing and being apertured to receive an angle cock attaching member.

3. For use in a railway car, the combination of a coupler housing having a striking plate at its forward end that projects outwardly beyond the sides of the housing, a coupler yoke key liner disposed on the side of the housing and spaced from the striking plate, and an angle cock bracket disposed between and engaging the striking plate and the liner, the bracket providing a relatively flat plate projecting outwardly from

the housing, and a U-shaped attaching member for securing the angle cock to the bracket, the bracket being apertured to receive the spaced arms of the attaching member.

5. For use in a railway car, the combination of a coupler housing having a striking plate at its forward end that projects outwardly beyond the sides of the housing, and an angle cock bracket disposed on the side wall of the housing directly behind the striking plate, the angle cock bracket being rigidly secured to the housing and having a portion thereof engaging and rigidly backing an outwardly projecting portion of the striking plate.

15 6. In a railway car having a coupler housing at one end thereof provided with a striking plate at its outer end that projects outwardly behind the sides of the housing, and a coupler yoke key liner disposed on a side wall of the housing, spaced from the striking plate, and projecting outwardly from the side wall of the housing, the provision of an angle cock bracket disposed between and engaging the striking plate and the liner and abutting against the side wall of the 20 housing, the bracket being in the form of a relatively flat plate projecting outwardly from the housing and being welded along its two sides to the striking plate and coupler yoke key liner respectively and along its inner side to the side wall of the housing, and a U-shaped attaching member for securing the angle cock to the bracket, the bracket being apertured adjacent to its free end to receive the spaced arms of the 25 attaching member.

30 35 CHARLES R. RADEY.
